CLAIM

The ornamental design for a table with built-in lamps, as shown and described.

DESCRIPTION

1. Table with built-in lamps

1.1 :Perspective

1.2 1 :Front

1.3 1 :Rear view

1.4 1 :Right

1.5 1 :Left

1.6 1 :Top

1.7 1 :Bottom

Table with built-in lamps, in particular for exhibitions. The broken line showing of portions of the table with built-in lamps is included for the purpose of illustrating environmental structure and forms no part of the claimed design.
